UNITED STATES PATENT OFFICE.

BENJAMIN F. CALDWELL, OF WHEELING, WEST VIRGINIA.

IMPLEMENT FOR BENDING METALLIC ROOFING-PLATES.

SPECIFICATION forming part of Letters Patent No. 341,315, dated May 4, 1886.

Application filed January 21, 1886. Serial No. 189,305. (No model.)

To all whom it may concern:

Be it known that I, BENJAMIN F. CALDWELL, a citizen of the United States, residing at Wheeling, in the county of Ohio and State 5 of West Virginia, have invented new and useful Improvements in Implements for Bending Metallic Roofing-Plates, of which the following is a specification.

This invention relates to an improvement 10 in the class of metal-plate-bending devices for which Letters Patent No. 329,713 were granted to me November 3, 1885, the object being to provide at little cost an implement for bending or turning the metal plates in applying 15 the roofing to buildings, and which shall be so inexpensive that it can be given gratuitously and without loss to each purchaser of roofing material.

My present invention consists of a tool for 20 bending metal roofing-plates, composed of a wooden head, a handle attached thereto, and sheet-iron bending-jaws secured to the under side of the heads, said jaws being separated by a V-shaped opening having a curved or 25 segmental top and smooth interior surfaces that facilitate the bending of the metal plates without liability of their edges binding within said jaws.

The invention is illustrated in the annexed 30 drawings, in which Figure 1 is a perspective view of my improved metal-plate-bending tool, and Fig. 2 is an end view of the same.

Referring to the drawings, the numeral 1 designates the head of the tool, which tool 35 head preferably consists of a wooden bar having a handle, 2, secured in any suitable manner midway between the ends of the head, said handle being preferably detachable.

To the under side of the tool-head are 40 secured the two fixed jaws 3, formed from a single piece of sheet metal bent to a suitable shape, as shown, and having its edges riveted or otherwise fastened to the opposite sides of the head. It will be observed that the sheet 45 metal comprising the jaws is so bent and shaped as to form two firmly-arranged jaws separated at their outer edges by a space of sufficient width to slip readily over and along the edges of the metal roofing-plates. The 50 inner surfaces of the jaws 3 converge from the head of the tool in an outward direction for

the purpose of providing an approximately V-shaped space or passage-way, 4, between the jaws, as shown in my former patent. In my above-mentioned patent, however, the inner edge of the head constituting the top of said V-shaped passage-way was shod with a flat metallic plate, whereas by my present invention the top wall, 5, of the V-shaped passage-way 4 is integral with the jaws 3, and is 60 curved or segmental in form. In connection with the smooth interior surfaces of the jaws this construction serves to facilitate a proper engagement of the tool with the metal plates to be bent, and by avoiding sharp angles between the jaws all liability of binding or kinking is obviated. By this construction, also, the head 1 is made nearly rectangular in cross-section instead of being wedge-shaped, as shown in my former patent. The under side 70 of the head 1 may be somewhat concaved, to conform to the segmental shape of the sheet metal at the top 5 of the passage-way between the jaws. As the space between the jaws 3 is inclosed at the top and both sides by smooth 75 metallic surfaces, the tool can be readily slid along the edges of the roofing-plates without catching on any roughened or uneven portion thereof, and the under side of the wooden head is also protected from injury.

This tool being composed entirely of wood and sheet-iron can be manufactured at such slight cost as to permit it to be furnished gratuitously to purchasers of metal roofing-plates.

It will be understood that I prefer to secure 85 the handle 2 in a detachable manner for convenience of shipping, and also to admit of its being detached from the head 1, so that both can be placed together within a package of roofing material.

Having thus described my invention, what I claim is—

1. A tool for bending metal roofing-plates, consisting of a head, a detachable handle, and two converging jaws composed of a single 95 piece of sheet metal secured to said head, substantially as described.

2. A tool for bending metal roofing-plates, consisting of a head, an attached handle, and two converging jaws composed of a single 100 piece of sheet metal rigidly secured to the sides of the head and having a curved metallic

portion at the top of the space between said jaws, substantially as described.

3. A tool for bending metal roofing-plates, consisting of a wooden head having a concaved under side and two converging jaws composed of a single piece of sheet metal having its edges rigidly secured to the sides of the head, said jaws being separated by a passage having a curved top integral with the jaws, substantially as described.

4. A tool for bending metal roofing-plates, consisting of a wooden head rectangular in cross-section and having a concaved lower side,

a handle attached to said head, and converging jaws composed of a single piece of sheet metal rigidly secured to the sides of the head and having a curved metallic portion at the top of the space between said jaws and integral therewith, substantially as described. 15

In testimony whereof I affix my signature in presence of two witnesses.

BENJAMIN F. CALDWELL.
